UNITED STATES PATENT OFFICE.

FERDINAND MORA CANDA, OF NEW YORK, N. Y.

METHOD OF AND APPARATUS FOR ROLLING BALLS.

1,367,299.

Specification of Letters Patent.

Patented Feb. 1, 1921.

Application filed October 10, 1919. Serial No. 329,774.

To all whom it may concern:

Be it known that I, FERDINAND MORA CANDA, a citizen of the United States of America, and resident of the borough of Manhattan, city, county, and State of New York, have invented Methods of and Apparatus for Rolling Balls, of which the following is a specification.

My invention relates to a method of and apparatus for forming balls, and is particularly intended for forming, from wrought iron and steel, balls adapted to be used in crusher mills and the like, but is also adapted and intended for forming balls of various other materials and for other uses—for example, lead shrapnel balls, lead shot, glass balls of various types and uses, etc. More particularly, however, I contemplate use of my invention in forming from steel, particularly hard steel, balls of relatively large diameter, particularly intended for use as crusher balls, since at the present time large diameter crusher balls are made by a process relatively expensive as compared with rolling operations, and involving the use of presses or hammers. In mentioning the above, however, I do not intend to suggest that I do not also contemplate the use of my invention for making balls of smaller size, for my invention is adapted for use in making small balls as well as large balls.

As an apparatus my invention comprises coacting grooved ball-forming rolls, together with pressing means which presses the material from which the balls are to be formed into the grooves of said coacting rolls, thereby forcing said material to take a form corresponding to that of the grooves of said rolls, instead of rotating idly outside of said grooves, as is apt to be the case otherwise, particularly when the material treated is of the nature of steel; and my invention further comprises pressing means which presses upon the equatorial portion only of the forming balls, thereby avoiding interference with the flow of the metal from the shoulders of the forming balls toward the equatorial portion. Other features of my invention, as an apparatus, will be pointed out hereafter. As a process my invention comprises grooving a rod or bar while rolling same until objects of approximate ball form are formed in said bar and are separated from one another, and then causing such objects to turn to new axes of rotation, and rolling the same on such new axes, thereby condensing the material

and perfecting the form of the ball; and my invention further comprises, as a method, grooving a bar by rolling so as to form objects of approximate ball form, and in such grooving pressing the material from the shoulders of the forming balls toward the equatorial portions thereof, while exerting pressure upon such partly formed balls on the equatorial portions only, so as not to interfere with the flow of the metal toward such equatorial portions. Other features of my invention, considered as a method, will be pointed out hereafter.

The object of my invention is to form balls, particularly of iron or steel, relatively inexpensively, rapidly, and in a simple manner and by simple apparatus.

I will now proceed to describe my invention with reference to the accompanying drawings, and will then point out the novel features in claims. In said drawings:

Figure 1 shows a central vertical transverse section of one form of ball rolling mill embodying my invention, and Fig. 2 shows a front elevation of that mill, a portion of the device being broken away.

Figs. 3, 4 and 5 are details of the presser for pressing the material from which the balls are to be formed against the rolls; Fig. 3 showing a transverse section of that presser, Fig. 4 a fragmentary top view thereof, and Fig. 5 an axial section of one of the presser rolls.

Fig. 6 shows a vertical transverse section of an alternative form of said apparatus, and Fig. 7 a front view of such alternative form.

Fig. 8 shows a detail transverse section of a presser of alternative form, in connection with rolls, this construction being applicable either to the apparatus shown in Figs. 1 and 2, or to the apparatus shown in Figs. 6 and 7.

Fig. 9 shows a top view of the arrangement shown in Fig. 8, the top roll having been omitted.

Fig. 10 is a view similar to Fig. 8, but showing a further alternative form of presser, and

Fig. 11 is a top view of the Fig. 10 construction with the top roll removed.

Fig. 12 is a transverse section of further alternative ball rolling apparatus embodying my invention and illustrated more or less diagrammatically.

Figs. 13, 14 and 15 are diagrammatic views

illustrating various steps in the formation of balls according to my method; Fig. 13 shows an axial section of a portion of a bar in an early stage of the process of forming the 5 balls; Fig. 14 being a front elevation of a nearly completed ball group, the necks between the balls being about to be severed; and Fig. 15 is a side view of one of the balls after the severing thereof from the other 10 balls of its group, and after change of axis of rotation, as hereinafter described.

Referring first to Figs. 1 and 2: Numerals 1 and 2 designate grooved coating rolls mounted in suitable bearings in a frame comprising 15 housings 3 resting upon a suitable bed and a connecting top member 4. The grooves in rolls 1 and 2 conform to the shape of the object to be formed, being usually half round in profile so as to produce spheres; but I may 20 say at this point that while my apparatus is particularly intended for the production of articles of generally spherical form, yet it is obviously adapted for the production of other forms of the nature of objects of rotation; for example, ellipsoids; and such objects I include within the general term 25 "balls" I have not indicated specifically means for driving the rolls 1 and 2, but such means may be means such as are commonly 30 employed for driving the rolls of rolling mills, except that the rolls should be driven in the same direction, whereas the rolls of ordinary rod mills, for example, are commonly driven in opposite directions. The 35 relative direction of rotation of the two rolls 1 and 2 is indicated by arrows in Fig. 1. Likewise I have indicated no particular means for holding down the upper roll 1; but such holding down means, if required, 40 may be similar to the means for the same purpose employed in ordinary rolling-mills, such as are employed for rolling slabs, bars and rods.

5 designates a transverse presser-frame 45 mounted in suitable slide-bearings 6 in housings 3 and movable toward and from the rolls 1 and 2; and for so moving said presser-frame in and out I have indicated hydraulic ram devices 7 mounted in the housings 3; 50 which ram devices may be considered as diagrammatic representations of any suitable device or devices for moving the presser frame forward and back. 8 and 9 designate pipes for supplying fluid under pressure to 55 these ram devices 7, and it will be understood that the supply of fluid under pressure to these ram devices will be regulated by a suitable valve 7^a, so that the presser frame may either be pressed forward toward the rolls 1 and 2, or may be retracted.

10 designates a shelf upon which a bar to be formed may be placed, at a time when the presser frame 5 is retracted. Such bar, so placed on the shelf, rolls down the latter into 60 the space between said rolls 1 and 2 and the

presser 5, and then, the presser being advanced, said bar is forced against the ribs of the rolls 1 and 2, and as said rolls rotate said bar is rolled between the rolls 1 and 2, and, under the influence of the pressure exerted by presser 5, is gradually forced into the grooves of said rolls, partaking of the form of said grooves, until it is converted into a series of balls. The operation may be stopped while the several balls are still connected by narrow necks, or it may be continued until the several balls are severed one from another. When the operation has continued sufficiently far, the presser 5 is retracted by suitable operation of the ram devices 7, whereupon the balls will roll out from between rolls 1 and 2, and may then be withdrawn from the mill. If the operation is stopped before the balls are completely severed from one another, being 75 therefore still connected by narrow necks, it is easy to break these necks, particularly after the ball-bar has cooled. But in general, it will be preferable to continue the ball rolling operation until the balls are completely severed from one another. 80

11 in Figs. 1 and 2 designates the balls while still between the rolls 1 and 2, but at a stage where their rolling is practically completed, so that the presser 5 is about to be 85 retracted to permit the balls to roll out of the mill.

That portion of the presser 5 which bears upon the material to be formed into balls, preferably consists of a series of disks 12, 100 relatively narrow as compared with the grooves of the rolls 1 and 2, as will be seen in Fig. 2, and rounded at the edges; these rollers, therefore, press against the equatorial portion only of the forming balls. 105 This is an important consideration, particularly when the balls are to be of spherical or nearly spherical form, for the following reason: When the bar from which the balls are to be formed is first pressed by the 110 presser 5 against the rolls 1 and 2, the first result is a grooving of the bar by the ribs of these rolls, as a result of which the bar is divided into sections, each corresponding to one of the registering grooves of the rolls 115 1 and 2, these sections, however, being still connected. At this time, the bar from which the balls are to be formed, is rotating between the rolls 1 and 2 and the disks 12 of the presser. As the operation proceeds, and the ribs of the rolls 1 and 2 groove more deeply the said bar, the metal at the shoulders of the sections into which the said bar is divided is pressed inward toward the equatorial portions of the forming balls, the 120 diameter of the forming balls increasing somewhat near these equatorial portions. It is important that the presser rolls 1 and 2 shall not interfere with the progress of the metal of the forming balls toward the said 125 130

equatorial portions; and hence it is desirable that said rollers 12 be not concave, or at least be not concave with a curvature approximating that of the formed balls. In fact, these rollers may be plane-faced, and are so shown in the drawings.

As the ball forming operation proceeds, the necks joining the partly formed balls gradually become smaller until finally, and while the forming balls are still of greater diameter than the minimum space between the bottoms of the grooves of rolls 1 and 2, the said necks break, and thereupon the nearly formed balls commonly change their axes of rotation, turning in the grooves of rolls 1 and 2 so that they rotate about new axes. This is done without any operation of special mechanism and without special adjustment of the presser 5, and is an action of extreme importance, since, as a result of the acquiring of new axes of rotation, the remnants of the necks theretofore connecting the partly formed balls are rolled into the bodies of said balls, whereby the material is greatly condensed and very solid balls are produced.

The completed balls, of course, have a certain volume. The bar from which these balls are rolled preferably has a diameter, readily determined by calculation, such that each of the sections into which the bar is divided by the first grooving action of the rolls has a volume slightly greater than that of the finished ball. This compels a certain compression of the metal, and therefore a certain increase in density thereof, which is extremely desirable as tending to promote the formation of very solid balls; and it does not matter if the amount of metal in one of the ball sections exceeds somewhat slightly that amount of metal which, under the utmost conditions of pressure available, can be pressed into a true sphere; for, if there be a slight excess of metal, after the partly formed balls have changed their axes of rotation, as previously explained, the subsequent rolling may result in the formation of ball-like objects which are really slightly ellipsoidal, the new axis of rotation being the shorter, and being, commonly, about at right angles to what was the initial axis of rotation.

The turning of the balls to new axes of rotation is apparently due to engagement of the axial teats (the remains of the necks which joined the partly formed balls before rupture of such necks) with the sides of the grooves of rolls 1 and 2. It will be noted that in this operation the rolling of the bar into balls occurs while the said balls remain slightly to one side of a line joining the centers of rolls 1 and 2; and when the rolling operation is completed, and the presser 5 is retracted, the finished balls roll out on that same side of the rolls 1 and 2.

In the alternative construction, shown in Figs. 6 and 7, the rolls, here designated by numerals 1^a and 2^a, are placed side by side, the presser, 5^a, being arranged to move up and down substantially vertically. Otherwise, the construction is substantially the same as that of Figs. 1 and 2. In the operation of this apparatus of Figs. 6 and 7, however, it will usually be more convenient to regulate the size of the initial bar from which the balls are to be formed, so that the balls, when practically completed, may pass completely between rolls 1^a and 2^a, dropping out at the bottom.

It is of course desirable that the presser 5 may be capable of entering as far as possible between rolls 1 and 2, or 1^a and 2^a. In the arrangement shown in Figs. 3, 4 and 5, the journals 13 of the rolls 12 are mounted in members 14 secured to the presser bar 5^c, which members 14 may even be grooved slightly as at 15, to receive the ribs of the rolls 1 and 2. Instead of the pressure on the rolls 12 being taken entirely by the bearings of the spindles of said rolls, an arrangement such as shown in Figs. 8 and 9 may be employed, wherein, back of each roll 12, there are two rolls 16, themselves mounted in members 14^b. These rolls 16 receive pressure from the rolls 12, and constitute, in fact, roller bearings for the rolls 12.

Since the bar from which the balls are to be formed may not be of uniform cross-section throughout, it may be desirable to provide for slight individual latitude of movement of each of the several rollers 12. To that end, as shown in Fig. 10, these rollers 12 (together with rollers 16, if the latter be employed) may be mounted in bearings in individual members 14^a, mounted to slide back and forth slightly in slide bearings in the transverse presser member (here designated by numeral 5^a) a separate hydraulic ram device 17 being provided for each such member 14^a. It will be understood that all of these hydraulic ram devices 17 receive their motive fluid from the same source; and therefore they constitute automatic compensating means whereby each of the presser rolls 12 presses with substantially the same force against the material from which the balls are being formed, but nevertheless each of those presser rolls 12 may yield individually as required by the particular conditions affecting the forming of its particular ball.

In Fig. 12 I have indicated that one of the ball forming rolls, here designated by numeral 1^b may be of materially less diameter than the other said roll, here designated by numeral 2^b. The advantage of this arrangement is that it permits the presser roll 12 to enter farther between the two ball forming rolls than would otherwise be the case. When one of the rolls is much smaller than

the other, as indicated in Fig. 12, the plane of movement in and out of the presser, here designated by 5^b, may with advantage be oblique with reference to a line connecting the centers of said rolls, instead of being at right angles to such line as in Figs. 1 and 2 and 6 and 7.

In Figs. 13, 14 and 15 I have indicated somewhat diagrammatically successive stages 10 in the formation of balls according to my method. In Fig. 13, the bar from which the balls are to be formed has been grooved somewhat deeply by the action of the ribs of the ball-forming rolls, said bar having therefore been divided into ball sections 11^a. In this view the axis of rotation is 18—18. This view shows the beginning of the forming of the metal from the ends of each ball section toward the center.

20 Fig. 14 shows a bar after the formation of balls therefrom is nearly completed; the balls, here designated by numeral 11^b, being connected only by narrow necks which are so narrow that they are about to be severed 25 or broken.

Fig. 15 shows one of the nearly finished balls after it has been severed from the others of its group and after its axis of rotation has changed, as previously described. 30 In this figure 18—18 designates the former axis of rotation, and 19—19 the present axis of rotation.

What I claim is:

1. In a ball rolling apparatus, the combination of coacting grooved ball-forming rolls, pressing means and means for causing said pressing means to press material to be formed into balls into the space between said rolls, and into the grooves of said rolls.

40 2. In a ball rolling apparatus, the combination of coacting grooved ball-forming rolls, pressing means, said pressing means comprising a pressing member adapted to press against the material acted upon, and means for advancing said pressing member to press material to be formed into balls into the space between said rolls.

50 3. In a ball rolling apparatus, the combination of coacting grooved ball-forming rolls and pressing means arranged to press material to be formed into balls into the space between said rolls, and into the grooves of said rolls, said pressing means comprising a pressing roll adapted to press against the material acted upon, and means for advancing and retracting said pressing roll.

60 4. In a ball rolling apparatus, the combination of coacting grooved ball-forming rolls and pressing means arranged to press material to be formed into balls into the space between said rolls, and into the grooves of said rolls, said pressing means comprising a plurality of rollers, one for each forming ball, and each of a width such that it presses 65 against a narrow equatorial portion only of

its corresponding ball, and means for advancing and retracting said pressing rollers.

5. In a ball rolling apparatus, the combination of coacting grooved ball-forming rolls and pressing means arranged to press 70 material to be formed into balls into the space between said rolls, and into the grooves of said rolls, said pressing means comprising a plurality of rollers, with means for permitting individual slight movement of 75 each roller in and out, and means for advancing and retracting said rollers together.

6. In a ball rolling apparatus, the combination of coacting grooved ball-forming rolls and pressing means arranged to press 80 material to be formed into balls into the space between said rolls, and into the grooves of said rolls, said pressing means comprising a plurality of rollers, and means for advancing and retracting said rollers together, 85 whereby individual adjustment of said rollers with reference to the material being rolled is permitted.

7. In a ball rolling apparatus, the combination of three coacting rolls between which 90 material to be formed into balls may be rolled, at least one of said rolls being grooved, and at least one of said rolls being mounted for movement toward and from another of said rolls, and means for so moving 95 the same.

8. In a ball rolling apparatus, the combination of two coacting grooved ball-forming rolls located substantially one above the other and a third roll arranged to press material to be formed into balls into the space between said first-mentioned rolls, and means for advancing and retracting said third roll. 100

9. The herein described method of forming balls, which consists in rolling spaced 105 grooves into a rotating bar, and as said grooving proceeds pressing the material at the shoulders of the sections into which the bar is so divided toward the central portions of said sections while exerting pressure on the equatorial portions only of said sections to hold said sections in place while they are being subjected to the ball-forming operation at their ends.

10. The herein described method of forming balls, which consists in rolling spaced grooves into a rotating bar and thereby dividing said bar into sections connected by necks which grow progressively smaller as the grooving proceeds and at the same time 110 exerting pressure from the ends of said sections to change the form of said sections to ball form, and finally separating said sections one from another and causing them to change their axes of rotation and thereby 115 rolling into the body portions of said balls the remnants of the necks formerly connecting the sections, and condensing the metal of said balls.

11. The herein described method of form- 130

ing balls, which consists in rolling spaced grooves into a rotating bar the initial diameter of which is such as to provide a slight excess of metal as compared with the volume of the desired finished ball, and by said rolling forcing material from the bar-sections so formed toward the centers thereof, and applying pressure to the equatorial portions of the forming balls during such rolling while avoiding the application of peripheral pressure to the side portions so as not to interfere with the flow of material toward the center.

12. The herein described method of forming balls, which consists in rolling spaced grooves into a rotating bar the initial diameter of which is such as to provide a slight excess of metal as compared with the volume of the desired finished ball, and by said roll-

ing forcing material from the bar-sections so formed toward the centers thereof, applying pressure to the equatorial portions of the forming balls during such rolling while avoiding the application of peripheral pressure to the side portions so as not to interfere with the flow of material toward the center, and separating the sections one from another and causing them to change their axes of rotation and thereby condensing the metal in the former axial regions of said balls. 20
